UNITED STATES PATENT OFFICE.

HENRY F. GRAY, OF COLUMBUS, OHIO.

CLIP FOR WHIFFLETREES.

No. 858,353.

Specification of Letters Patent.

Patented May 14, 1907.

Application filed February 2, 1906. Serial No. 299,203.

To all whom it may concern:

Be it known that I, HENRY F. GRAY, a citizen of the United States, residing at Columbus, in the county of Franklin and State of Ohio, have invented certain new and useful Improvements in Clips for Whiffletrees and the Like; and I do hereby declare the following to be a full, clear, and exact description of the invention, such as will enable others skilled in the art to which it appertains to make and use the same.

The object of this invention is to provide an improved clip for swing trees and the like, of simple, effective and economical form, that is adapted to be secured in place without the use of a bolt and nut and the tool or tools necessary to apply them.

The invention resides in the construction hereinafter described and claimed.

20 In the accompanying drawings in which I have shown one embodiment of the invention—Figure 1 is a view in side elevation; Fig. 2 is a plan view; and Fig. 3 is an end view looking toward the left Fig. 1.

25 In the views 1 designates what I shall call the draft member and 2 the locking member.

The draft member is shown to comprise a body portion 1^a adapted to fit slightly more than half way around the wood of the tree 30 and extending beyond both terminals of a plane bisecting the wood axially. The forward end of the draft member has cast integral with it a loop 1^b for the attachment of the traces of the harnessed animal. The 35 rear end of the draft member has an eye 1^c to receive a hook on the locking member 2. The metal between the eye and the body portion of the draft member is recessed, as seen at 1^d, and the upper side of the metal at 40 this portion made with a groove 1^e.

The body of the locking member 2 is preferably so formed as to fit only partially around the lower half of the wood and so as to allow for some compression on the wood before it 45 can contact at its forward end with the corresponding end of the draft member. The rear end of this member is furnished with a hook 2^a to enter and so engage the eye 1^c as to latch the two members together at that 50 end, and the forward end of this locking member is furnished with a tongue 2^b that reaches up through the recess at 1^d. This tongue is made with a slot 2^c.

To lock the parts together and to clamp 55 them tightly on the wood of the tree I use a wedge 3 that I drive through the slot 2^c, the

groove 1^e serving to guide the wedge and protect it from distortion. After the wedge is driven tightly into place its smaller end can be bent down, as best seen in Fig. 3, to lock it 60 from longitudinal movement.

It will be observed that this clip can be applied and removed without the use of a wrench or other special tool; and also that it is less likely to become loose than a clip secured with a bolt and nut. The farmer in the field can with a small piece of rock or iron either apply or remove the clip.

It will be observed that the draft, being on the line a—b, Fig. 1, is chiefly on the upper 70 member and hence there is little pressure on the connecting parts.

What I claim and desire to secure by Letters Patent is:

1. A clip comprising two wood-embracing 75 members, one of said members having integral therewith at one end a draft loop and the other having at the corresponding end a perforated tongue integral therewith, the said tongue adapted to pass through said looped end of the first mentioned member and receive a key wedge lying on one side of the loop, and means integral with the members for latching them together at the opposite ends of the members. 85

2. A clip comprising, in combination, two wood-embracing members with means for securing them together at one end, and means for locking them together at the opposite end, one of said members having a draft loop 90 formed integral therewith and said member at its wood-embracing portion extending more than half way around the circumference of the wood and beyond both terminals of a plane bisecting axially the wood. 95

3. A clip comprising, in combination, two wood-embracing members with means for securing them together at one end, and means for locking them together at the opposite end, one of said members having a loop or device to which the harness of a draft animal can be attached and said member at its wood-embracing portion extending more than half way around the circumference of the wood and beyond both terminals of a plane bisecting axially the wood. 100

4. A clip comprising two wood-embracing members, one of said members having integral therewith at one end a draft loop and a transverse groove at the outer side of the member at the base of the loop and the other member having at the corresponding end a 110

perforated tongue integral therewith, the
said tongue adapted to pass through said
looped end of the first mentioned member
and receive a key wedge lying on one side of
5 the loop and in said groove, and means inte-
gral with the members for latching them to-
gether at the opposite ends of the members.

In testimony whereof I affix my signature,
in presence of two witnesses.

HENRY F. GRAY.
